UNITED STATES PATENT OFFICE.

SYRUS SHIRLEY SCOTT, OF CARROLLTON, MISSOURI, ASSIGNOR OF ONE-HALF TO CLARK E. JACOBY, OF KANSAS CITY, MISSOURI.

MAT FOR REVETMENT WORK AND PROCESS OF MAKING SAME.

Application filed December 21, 1925. Serial No. 73,833.

This invention relates to mats for use in the revetment of river banks and the like and has for one of its objects to produce a new and improved mat of combined woven wire and willow or other suitable tree growths or brush, in which the willow and wire are so intertwined that the latter reliably maintain the former in position and the mat as a whole is as effective as a strictly willow woven mat.

Heretofore, it has been customary in weaving mats to lay a plurality of parallel strips of material and then to intertwine cross-wise strips through the first named strips by passing said cross-wise strips first over and then under the strips first placed in position. It will be apparent that this method of weaving is extremely slow and is, therefore, very high in cost. A second object of the invention is to disclose a new, novel, useful, efficient and inexpensive method of weaving a mat composed of a combination of willows or the like and wire fabric.

With the objects named in view, the invention consists in certain features of construction and combination of parts as hereinafter described and claimed; and in order that it may be fully understood, reference is to be had to the accompanying drawing, in which:—

Figure 1 is a plan view of a mat in the process of construction, illustrating at the right the mat as it appears when complete.

Figure 2 is a side view of the mat as shown in Figure 1.

Figures 3 to 7 inclusive, illustrate diagrammatically the various steps employed in the new and novel process of weaving the mat.

In the said drawing, where like reference characters identify corresponding parts in all of the figures, a plurality of rolls, the number depending on the width of the mat, of suitable wire mesh 1 of any desired width, weight and length, are placed along the ground and unrolled alternately in opposite directions (see Figure 3), a distance equal to the width of the rows of mat material W it is desired to form. The meeting or adjoining corners of the wire fabric are tightly tied together by suitable ties 2.

For convenience in the explanation of the process of weaving, the rolls of material as first placed on the ground will be identified

as "a" and "b" (see Figures 3 and 4). As soon as the rolls have been spaced as shown in Figures 3 and 4, the first row "x" of willows or the like W is packed into position, it being apparent that practically all sizes of material may be placed without necessitating special cutting and that any thickness of mat may be produced by regulating the quantity of material W placed in position.

The first row "x" of material having been placed, the operators lift the rolls of wire "a" to the right, as illustrated, it being evident that each roll "a" will be received between a pair of rolls "b." The rolls "b" are now lifted over the mat material of row "x" and drawn tight, the adjacent corners of the rolls "a" and "b" (see Figure 1), being now preferably tightly wired or secured together as at 2 to hold the row "x" in a tightly compacted mass.

The rolls "b" are now unrolled a sufficient distance, see Figure 5, to provide the proper space for the reception of a row "y" of mat material. The row "y" of mat material is now placed, and the rolls "a" are carried over the top of said row, and placed on the ground between the rolls "b." The adjacent corners of the wire fabric are now preferably tightly wired or otherwise secured together as at 2, as shown clearly in Figure 1, to hold the row "y" in compacted form.

The rolls "b" are now carried back over the row "y," see Figure 6, and placed between said row "y" and the row "x," the rolls "a" being unrolled a sufficient distance for the reception of the row "z" of necessary mat material. After the row "z" of mat material has been placed the rolls "b," see Figure 7, are brought over the top of said row and placed on the ground between the rolls "a," and the adjacent corners of the wire fabric are preferably tightly wired together as at 2 in Figure 1, to hold said row in compacted condition.

The rolls "a" are now carried back over the row "z," see Figure 7, and the process of forming the row "v" of mat material is carried out in all respects similar to the process described in connection with Figures 5 and 6. A complete cycle of operations in the method of carrying out the process of the invention has now been completed.

It will be apparent that the process as described is continued until a mat of any de-

sired length has been formed and that whenever a roll of wire fabric has been exhausted, another roll may be spliced on at the end as will be readily understood.

In connection with the process of weaving a mat, it will be evident that it lends itself particularly convenient to weaving at the stern of a barge or the like, and the feeding of the completed mat directly off the barge into the desired position, or the mat may be completely woven on the bank and then placed in the most convenient manner, where necessary.

A mat constructed in accordance with the invention may be tied, staked or weighted to hold it in position in any of the common and well known methods now in use. It is desired to emphasize the point that the process of weaving is universal in its character, that is the same process lends itself to use in weaving any thickness of mat with the rows of material of any desired width, and that a continuous mat of any width or length may be just as conveniently woven.

From the above description, it will be apparent that I have produced a mat and process of weaving which possesses all of the features of advantage pointed out as desirable, and while I have described and claimed the preferred form of the invention, I reserve the right to make all changes properly falling within the spirit and scope of the appended claims.

I claim:

1. The process of weaving a mat of mat material and wire fabric comprising the placing of a plurality of rows of rolls of fabric alternately unrolled a predetermined distance in opposite directions, compacting a quantity of mat material in the space thus provided between the rows, then alternately unrolling the rolls of one row over the mat material to bind the same in position, and removing the other row of rolls so that it shall not interfere with the process.

2. The process of weaving a mat of mat material and wire fabric comprising the placing of a plurality of rows of rolls of fabric alternately unrolled a predetermined distance in opposite directions, compacting a quantity of mat material in the space thus provided between the rows, alternately removing the rolls of one from position, and then unrolling the rolls of the other row over the mat material to bind the same in position.

3. The process of weaving a mat of mat material and wire fabric comprising the placing of a pair of rows of rolls of fabric alternately unrolled a predetermined distance in opposite directions, compacting a quantity of mat material in the space thus provided between the rows, then alternately unrolling the rolls of each row to the right

and to the left so that the fabric of each row may alternately overlie and underlie the mat material to bind the same in position.

4. The process of weaving a mat of mat material and wire fabric comprising the placing of a pair of rows of rolls of fabric alternately unrolled a predetermined distance in opposite directions, unrolling the rolls of one row over the mat material to bind the same in position, unrolling the rolls of the other row in the opposite direction over the mat material to remove them from interference with the process, unrolling the rolls of the first-named row a predetermined distance, compacting material on the length of fabric thus exposed, unrolling the rolls of the second-named row over the row of mat material to secure the same in position, then alternately repeating the process for the full length of the mat.

5. The process of weaving a mat of mat material and wire fabric comprising the placing of a pair of rows of rolls of fabric alternately unrolled a predetermined distance in opposite directions, securing the adjacent corners of the fabric together, compacting a quantity of mat material in the space thus provided between the rows, then unrolling the rolls of one row over the mat material to bind the same in position, securing the adjacent edges of the fabric together, and then removing the other row of rolls so that it shall not interfere with the process.

6. A mat comprising a plurality of parallel rows of mat material, and a plurality of rows of wire fabric placed at right angles to the mat material, the wire fabric of each row alternately overlying and underlying adjacent rows of mat material.

7. A mat comprising a plurality of parallel rows of mat material, and a plurality of rows of wire fabric placed at right angles to the mat material, the wire fabric of each row alternately overlying and underlying adjacent rows of mat material and the rows of wire fabric being so related that adjacent rows are alternately overlying and underlying any particular row of mat material.

8. A mat comprising a plurality of parallel rows of mat material, a plurality of rows of wire fabric placed at right angles to the mat material, the wire fabric of each row alternately overlying and underlying adjacent rows of mat material and the rows of wire fabric being so related that adjacent rows are alternately overlying and underlying any particular row of mat material, and means securing together the adjacent corners of said wire fabric rows.

In witness whereof I hereunto affix my signature.

SYRUS SHIRLEY SCOTT.
